UNITED STATES PATENT OFFICE.

JAMES D. BRUCE AND ALEXANDER D. BRUCE, OF FRAMINGHAM, MASSACHUSETTS.

BLADE STROPPER.

Application filed June 7, 1927. Serial No. 197,072.

This invention relates to a blade-stropper which includes a bed supporting a stropping member, such as a piece of stropping leather, and a carrier guided by the bed and having 5 means for presenting opposite edges of a two-edged safety-razor blade alternately to the stropping member, the stropper being adapted to reciprocate the blade over the stropping member and strop one edge during a movement in one direction, and the opposite edge during a movement in the opposite direction.

The invention is embodied in certain improvements, the nature and objects of which 15 are hereinafter described.

Of the accompanying drawings forming a part of this specification,—

Figure 1 is a top plan view of a blade-stropper embodying the invention.

20 Figure 2 is a side view of the same.

Figure 3 is a fragmentary side view similar to a portion of Figure 2, showing a different presentation of the blade to the stropper member.

25 Figure 4 is a bottom plan view, showing a portion of the stropper.

Figure 5 is a section on line 5—5 of Figure 1.

The same reference characters indicate the 30 same parts in all of the figures.

In the drawings, 12 designates a bed, which may be a metal plate having flat sides and parallel longitudinal edges, adapted to cooperate with the grooved rollers hereinafter 35 described. The bed may be supported by feet 13, fixed to its opposite ends. A stropping member 14 of leather, or other suitable material, is fixed, as by screws 15, to the bed. A layer 16, of compressible cushioning material, may be interposed between the stropping member and the bed-plate. A carrier 40 is movable on and guided by the bed, and is provided with a rock-shaft 17, adapted to hold a two-edged safety-razor blade 18. The carrier is preferably made from a single 45 piece of sheet metal and includes a body portion 19, and ears 20 and 21, integral with the body portion and bent upward from opposite ends thereof. The ear 20 is provided 50 with spaced apart stops 22 and 23, preferably integral with the ear, and bent outwardly therefrom. The ears 20 and 21 are provided with bearings in which the end portions of the rock-shaft 17 are journaled.

55 The rock-shaft is provided with means hereinafter described for releasably holding

the blade 18, and with a crank composed of an arm 24, fixed to one end of the rock-shaft, and a handle 25, to be grasped by the operator. The crank-arm 24 is arranged to oscillate between the stops 22 and 23, and to abut said stops alternately, as shown by Figures 2 and 3, and impel the carrier through the abutted stop. When the crank-arm abuts the stop 22, and the crank is forced by the operator in the direction of arrow X (Figure 2), the carrier and blade are also moved in the direction of arrow X. When the crank-arm abuts the stop 23, and the crank is forced in the direction of arrow v (Figure 3), the carrier and blade are moved in the direction of arrow v. The arrangement is such that when the crank is turned to abut one stop, one edge of the blade is a trailing or following edge and is pressed against the stropping member, and when the crank is turned to abut the other stop, the opposite edge of the blade is a trailing or following edge and is pressed against the stropping member. A swinging movement of the crank in either 60 direction, therefore, enables the crank to impel the carrier through one of the stops, and at the same time press the blade edge, which is, for the time being, the rear or trailing edge, against the stropping member. The advancing or forward edge of the blade is always raised, so that it cannot cut the stropping member.

The carrier is provided with runners engaging the guiding edges of the bed 12, and maintaining the rock-shaft 17, substantially at right angles with the bed and the stropping member. In other words, the rock-shaft is maintained substantially at right angles with its path of movement over the stropping member. The runners are preferably antifriction rollers turning on vertical axes supported by the carrier, and in rolling contact with the guiding edges of the bed. The rollers are preferably pressed yieldingly against the guiding edges of the bed to prevent a loose bearing of the rollers on said edges, as next described.

The sheet metal body 12 of the carrier is provided at one end with fixed spaced apart studs 26, on which are journaled rollers 27, having grooved peripheries engaging one of the guiding edges of the bed 12, said edge and the rollers being preferably rounded, as shown by Figure 5. To the opposite end of 105 the body 12 is pivoted at 28 (Figure 4) a roller holder 29, having a stud 30, on which

is journaled a single roller 31, having a grooved periphery engaging the opposite guiding edge of the bed. A contractile spring 32, engaged at one end with an ear 33, on the body 19, and at the opposite end with an ear 34 on the pivoted holder 29, directly maintains the roller 31 in yielding contact with the guiding edge with which it is engaged, and indirectly maintains the rollers 27 in yielding contact with the opposite guiding edge. When the holder 29 is displaced, as indicated by dotted lines in Figure 4, the carrier may be removed from the bed. The carrier body 19 and its ear 21 are provided with a slot 35 (Figure 4) in which the roller 31 is movable toward and from the bed.

We will now describe the means shown for releasably securing the blade 18 to the rock-shaft 17.

20 The described yielding pressure of the rollers against the guiding edges of the bed, causes said rollers to sufficiently oppose movement of the carrier on the bed to cause a suitable pressure of the trailing blade edge 25 against the stropping member, by the pressure of the crank against the abutted stop 22 or 23. In other words, if the rollers were not pressed yieldingly against the guiding edges of the bed, and were allowed to run loosely thereon, the carrier might be so freely movable on the guiding edges that the pressure of the crank against the abutted stop would 30 impel the carrier without sufficiently turning the rock-shaft to cause desirably positive pressure of the trailing blade edge against 35 the stropping member.

The rock-shaft is cut away between its ends, to form a flat blade seat between the portions journaled in the carrier ears 20 and 21, 40 as best shown by Figure 5. Fixed to the rock-shaft and projecting from the blade seat near one end thereof, is a hooked stud 37, adapted to engage the margin of one of the usual orifices 38, in the longitudinal center of the 45 blade. The portion of the rock-shaft journaled in the ear 21 is tubular, and its bore constitutes a guide in which a rod 39 is longitudinally movable. The rod is provided with a hooked stud 40, adapted to engage the margin of another blade orifice 38. The rod 39 is provided with a head or push member 41, between which and the rock-shaft is interposed a normally expanded spring 42, which acts to hold the stud 40 in engagement with 50 the blade. When the push piece 41 is pressed inward, the blade is released. Withdrawal of the rod 39 from the rock-shaft is prevented by a pin 44 (Figure 5), fixed to the rod, and a slot 45 in the rock-shaft, receiving the pin.

60 The flat blade seat on the rock-shaft 17 is arranged in relation to the crank 24 and stops 22 and 23, to cause a predetermined inclination of the seat relative to the stropping member, when the crank abuts one of the stops, 65 and a different predetermined inclination,

when the crank abuts the other stop, so that corresponding predetermined transverse inclinations of the blade, confined as described, on said seat, are caused by the cooperation of the crank with the stops. When the crank 70 abuts the stop 22, the blade has the transverse inclination shown by Figure 2, and when the crank abuts the stop 23, the blade has the transverse inclination shown by Figure 3.

We claim:

1. A stropper for a two-edged razor-blade, comprising a bed having longitudinal guides at its opposite edges, a strop fixed to, and supported by, the bed, a carrier having runners engaged with said guides, and upstanding ears at opposite ends of the carrier, one of said ears being provided with spaced apart stops, a blade-holding rock-shaft journaled in said ears and provided with a crank oscillatable between, and adapted to alternately abut said stops, and with means for engaging a two-edged blade and holding the same in either of two transversely inclined positions, each determined by the handle and one of the stops, the arrangement being such that when the handle abuts one stop, and exerts pressure thereon to impel the carrier in one direction, one of the blade edges trails behind the carrier and is pressed against the strop, and when the handle abuts the other stop, and exerts pressure thereon to impel the carrier in the opposite direction, the other blade edge trails behind the carrier and is pressed against the strop, the advancing or forward edge being raised during each movement of the carrier, so that it cannot cut the strop, the carrier being provided at its opposite ends with grooved rollers engaging said guides, and with means for yieldingly pressing said rollers inwardly against the guides, so that the rollers sufficiently oppose movement of the carrier on the guides to ensure pressure of the trailing blade edge against the strop, by pressure of the crank against the abutting stop.

2. A stropper as specified by claim 1, the carrier being provided at one end with grooved rollers engaging one of the guides, and at the opposite end with a pivoted roller holder having a grooved roller engaging the opposite guide, and with a spring which directly presses said roller against the last-mentioned guide, and indirectly presses the other rollers against the opposite guide.

3. A stropper as specified by claim 1, the rock-shaft being provided with a flat blade seat between its ends, arranged in relation to the crank and the stops, to cause a predetermined inclination of the seat relative to the strop, when the crank abuts one of the stops, and a different predetermined inclination of the seat when the crank abuts the other stop, and with blade-engaging means projecting from the seat and adapted to confine the blade on the seat and cause corresponding trans-

verse inclinations of the blade relative to the strop, said means including a hooked stud fixed to, and projecting from, the blade seat, and adapted to engage the margin of a blade orifice, and a spring-pressed rod movable in a longitudinal guide in the rock-shaft, and provided with a hooked stud projecting from the seat and adapted to engage the margin of

another blade orifice, the rod being provided with a push member whereby it may be displaced to release the blade. 10

In testimony whereof we have affixed our signatures.

JAMES D. BRUCE.

ALEXANDER D. BRUCE.
